UNITED STATES PATENT OFFICE.

OTIS E. BROWN, OF BROCKTON, MASSACHUSETTS, ASSIGNOR TO THE SINGER MANUFACTURING COMPANY, A CORPORATION OF NEW JERSEY.

WAX-THREAD MACHINE.

1,002,217.

Specification of Letters Patent.

Patented Sept. 5, 1911.

Application filed February 27, 1909. Serial No. 480,338.

To all whom it may concern:

Be it known that I, OTIS E. BROWN, a citizen of the United States, residing at Brockton, in the county of Plymouth and State of Massachusetts, have invented certain new and useful Improvements in Wax-Thread Machines, of which the following is a specification, reference being had therein to the accompanying drawings.

10 This invention has for its object to provide an easy running and efficient mechanism particularly adapted for machines for stitching with the use of waxed thread; and it consists in the combination and arrangement of parts herein shown and described and pointed out in the appended claims.

One of the characteristic features of the present improvement is the employment of cranks and eccentrics for actuating the 20 thread-handling devices in lieu of the cams commonly employed for such purpose in stitching machines for the heavier class of work, whereby light running and freedom from excessive noise is assured, while the 25 avoidance of harsh movements of the parts insures durability of the mechanism.

In the accompanying drawings, Figure 1 is a sectional front side elevation of a machine embodying the present improvements 30 and Fig. 2 a plan of the same. Fig. 3 is a perspective view of the machine with the frame indicated mainly in dotted outline, and with the rear side of the wax-pot broken out to expose its internal construction. Fig. 4 is a front end view of the forward portion 35 of the machine, Fig. 5 a rear end view of the actuating mechanism for the thread-handling devices and Fig. 6 a transverse section of the head of the bracket-arm and mechanism contained therein, looking forwardly.

Fig. 7 is a detail view of the feed-actuating mechanism and Fig. 8 an enlarged cross-section representing the feed regulating means. Fig. 9 is a perspective view showing 45 a portion of the presser-foot lifting device and Fig. 10 a perspective view of the clutch mechanism therefor. Fig. 11 is a plan view of the thread retainer co-operating with the take-up in controlling the upper thread. 50 Fig. 12 is a perspective view of the take-up arm and parts carried thereby. Fig. 13 is a transverse section of the wax-pot and thread leading and stripping mechanism contained therein, and Fig. 14 a perspective view of

the thread leading and stripping means contained within the wax-pot. 55

As represented in the drawings, the frame of the machine comprises the hollow standard 1 with cylindrical work-supporting arm or horn 2 and hollow overhanging bracket-arm 3 terminating in the usual head 4. The needle 5 is mounted in the reciprocating needle-bar 6 journaled in the upper and lower bearings 7 of the laterally movable needle-frame 8. The needle-bar carries the 65 usual collar 9 with lateral stud 10 embraced by one end of the link 11 whose opposite end is connected with the stud 12 carried by the forwardly projecting crank-arm 13 of the needle-actuating rock-shaft 14, mounted in 70 suitable bearings upon and longitudinally of the overhanging bracket-arm 3. At its rearward end, the rock-shaft 14 is provided with a depending crank-arm 15 connected by means of a link 16 to the upper end of a link-bar 17 whose lower end is provided with a 75 strap 18 embracing the actuating crank 19 formed in the driving shaft 20 which is journaled within and transversely of the standard 1 parallel with the needle-actuating 80 rock-shaft 14.

Loosely mounted upon a shaft 21 journaled upon center screws 22 in the bearing lugs 23 extending rearwardly from the standard 1 is a sleeve 24 confined between 85 thrust-collars 26 and constituting a member of a swinging yoke 27 which carries the conical center screws 28 entering the similarly apertured bosses 29 extending from the opposite faces of the link-bar 17. In following 90 the rotary movements of the actuating crank 19 of the driving shaft, the link-bar 17 is thus adapted to move bodily upon the axis of oscillation of the yoke or radius-bar 27, whereby the upper end of the link-bar 17 95 connected with the link 16 is moved in a substantially elliptical path with a nearly vertical major axis adjacent the rock-shaft 14.

The several members of the mechanism 100 are so proportioned and arranged that when the upper end of the link-bar is rising from its extreme lower and rearward position, a little below the position indicated in dotted lines in Fig. 5, its relation to the depending 105 arm 15 of the rock-shaft is such that the needle is in its lowest position. As the link-bar rises to and slightly above the dotted

line position of Fig. 5, the arm 15 is swung slightly forwardly to raise the needle sufficiently to throw out its loop for the shuttle, after which it moves upwardly and forwardly practically in an arc described by the link 16, whereby the arm 15 is maintained stationary for a time sufficient to permit the distention of the needle-thread loop by the shuttle and the advance of the material under the feeding action, after which the approach of the upper end of the link-bar to the rock-shaft and its continued movement beneath the same causes the rapid movement of the crank-arm 15 to extreme forward position and consequent rise of the needle to its highest position.

In the descent and backward movement of the upper end of the link-bar 17, the latter reaches its most advantageous relation with the crank-arm 15 just as the needle is entering the goods for a succeeding stitch, thus insuring the application of the full force of the mechanism at the time when the greatest load is imposed thereon.

The lower portion of the link-bar 17 is provided adjacent the strap 18 with a rearward offset or extension carrying a stud-screw 30 embraced by one end of a pitman 31 whose opposite end embraces a similar stud-screw 32 carried by a lateral crank-arm 33 of a rocking sleeve 34 which is provided with a forked arm 35 which embraces a roller-stud 36 carried by a crank-arm 37 upon the rearward end of the shuttle actuating rock-shaft 38 which is journaled in bearings 39 within the cylinder arm 2 and carries at its forward end the shuttle-driver 40. The shuttle 41 is of the well-known Singer oscillating type, provided with the barrel thread-case 42 and fitted to oscillate within a race 43 at the forward end of the cylinder arm 2, the throat 44 and heel 45 of the shuttle being alternately engaged by the arms of the shuttle-driver in a well-known manner.

By the particular arrangement of the link connection 31 with the link-bar 17 described above, the shuttle movements are timed, as before recited, so as to coöperate with the needle in the manipulation of the upper thread so as to seize and distend the needle-thread loops while the needle-eye is beneath the work, thus avoiding any undue strain upon the thread in the loop-seizing and casting operations which would be produced in case the rise of the needle was hastened or the action of the shuttle upon the needle-thread was delayed.

Mounted loosely upon the rock-shaft 14 between the thrust-collars 46 is a rocking sleeve 47 having two rearwardly projecting and angularly disposed arms 48 and 49, the former of which is connected by means of the link 50 with the upper end of the link-bar 17 by means of the stud-screw 51 to which the link 16 is connected. The crank-arm 49

of the sleeve 47 is connected by means of a bent link 52 with a crank-arm 53 fixed upon the take-up rock-shaft 54 mounted in suitable bearings 55 upon the bracket-arm 3. The rock-shaft 54 is provided intermediate 72 said bearings, for a reason presently to be described, with an offset portion 56 between which and its extreme forward end it is formed with an axial thread-aperture 57.

Upon the forward end of the rock-shaft 75 54 is fixed the hub 58 of the take-up arm or lever 59 carrying the grooved tension-wheel 60 one side of which is disposed substantially in alignment with the thread aperture of the take-up rock-shaft, the tension wheel being 80 journaled upon the pin 61 fitted to a suitable transverse bearing of the take-up arm and having a head 62 normally resting upon the outer face of the take-up wheel, or a washer 63 intermediate the same, a spring 64 being 85 interposed between the bearing in the arm 59 and a washer 65 confined adjustably upon the pin by means of a nut 66 applied to the threaded opposite end of the pin, whereby the tension wheel 60 is normally subjected 90 to a slight frictional drag. The take-up arm 59 carries at its outer end a grooved thread-wheel 67 mounted upon the shouldered stud-screw 68 and intermediate its ends a similarly grooved thread-wheel 69 mounted upon the stud-screw 70, each of said thread-wheels 95 being embraced between the expanded adjacent ends of the guard loops 71 and 72, respectively.

Adjustably fixed upon the head of the 100 bracket-arm by means of the fastening screw 73 is a downwardly and forwardly inclined arm 74 carrying at its outer end a stud-screw 75 upon which is journaled a stationary thread-wheel 76 embraced within a thread guard-loop 77 similarly to those carried by the take-up arm. Adjacent and above the stationary thread-wheel is arranged a pair of thread retaining plates 78 79, the one being rigidly connected to and preferably integrally formed with the bracket-piece 80 secured by means of a suitable fastening screw to the head of the bracket-arm, while the other, formed of 105 spring metal, is secured to said bracket by 110 means of the fastening screws 81.

The needle-thread is led from the hollow forward end of the take-up rock shaft 54 around the tension-wheel 60, thence beneath a guide-roller 82 upon the take-up arm 59 below the same and between the grooved guide-rollers 83 mounted upon stud-screws 84 in the bracket-piece 83 secured to the needle-frame 8 by the fastening screw 86, and thence through the guide-strap 87 embracing the lower needle-bar bearing 7 to the eye of the needle 5. Between the guide roll 82 and the rollers 83 the thread is confined against disarrangement by passing through 120 the guard-loops 71, 77 and 72. The take- 125

up arm assumes its lowest position just after the point of the shuttle has seized the needle-thread loop, and starts its rising movement without any immediate effect upon the thread extending from the roll 82 to the grooved rollers 83 until the shuttle has reached its most advanced position and the eye of the needle has risen above the work, when the grooved rollers 67 and 69 engage the thread below and upon opposite sides of the stationary roller 76, when the continued rise of the take-up arm 59 causes the bending of the thread around the stationary roller 76 for taking up the slack needle-thread and setting the stitch, the latter being effected as the take-up arm and the needle reach their highest positions. In the rising movement of the take-up arm, one of the limbs of the needle-thread loop between the stationary roller 76 and the roller 67 is drawn between the flaring forward edges of the thread-retaining plates 78 and 79, between which it is lightly grasped. As the needle and take-up arm perform the first part of their descending movements, the looped portion of needle thread engaged by the take-up arm is released more rapidly than it can be accommodated by the descending needle, but being lightly retained between the plates 78 and 79, that portion of the thread between the same and the needle eye is not slackened to such extent as to endanger the entangling of the thread while the needle is descending, but as soon as it is engaged by the point of the shuttle, it is readily drawn out of the retainer in the expansion of the loop in the loop-casting operation.

The tension wheel has been described as having one side in alinement with the thread delivery aperture of the take-up rock-shaft, by which arrangement its supporting pin 61 is disposed in eccentric relation to the axis of motion of the take-up arm. Journalized in a suitable fixed bearing 88 upon the head of the bracket-arm is a rocking pin 89 having a diametrical slit 90 in its forward end in which is inserted one end of a coiled spring 91 whose opposite end rests against a fixed shoulder afforded by a stud-screw 92 upon a stationary part of the machine. The pin 89 is provided with an upwardly projecting arm 93 which carries a contact screw 94 whose point is adapted to normally rest upon a lug 95 upon a fixed part of the head of the bracket-arm, the circular adjustment of the rocking pin 89 being effected by turning the contact screw 94 in one or the other direction, as will be readily understood. Within the slit in the forward end of the rocking pin 89 is inserted one end of a substantially U-shaped spring nipper-lever 96 which is secured in place by means of the clamp-screw 97. The free longer limb of the nipper-lever 96 is formed with a seg-

mental contact portion 98 adapted to receive the rounded head of the journal pin 61 of the tension wheel 60. As the take-up arm rises for setting the stitch, the head of the pin 61 engages the bearing portion 98 of the nipper-spring 96, and is thereby yieldingly forced harder against the adjacent face of the tension wheel, serving to practically lock it against rotation under the action of the take-up upon the thread, whereby the final portion of the take-up movement is exerted in merely tightening the portion of thread between the take-up wheel and the work, and thereby setting the stitch firmly in the latter.

The rearward side of the bracket-arm 3 is provided with a projecting lug 99 embraced by the alined centering screws 100 carried by spaced lugs 101 projecting from one end of the wax pot 102 formed in two compartments separated by a vertical partition 103 with a series of apertures 104 near the bottom for communication between such compartments. The larger of these compartments constitutes a reservoir for receiving the wax, and the smaller compartment is that into which the thread is led for the waxing operation.

As herein shown, the thread-guiding devices are mounted upon a bracket 105 secured to a suitable seat upon one edge of the waxing compartment by means of screws 106 and dowel pins 106^x. The bracket 105 is provided with an arm or standard 107 carrying the disk tension device 108 of well-known construction, the thread being led to the same through an eyeflet 109 whose shank is secured to the bracket by means of a screw 110. Depending from the body of the bracket 105 is a rigid arm 111 carrying a fulcrum screw-stud 112 upon which is journaled a rock-lever having mounted upon its lower arm 113 a stud-screw 114 affording a bearing for the grooved thread-wheel 115 mounted within a peripherally slotted cylindrical housing 116. To the upper end of the other arm 117 of the rock-lever is secured by means of a screw 118 the shank of the movable stripper-blade 119 provided with a thread notch 120 in its forward edge and curved concentrically with the pivotal stud 112 to coöperate with the similarly curved fixed stripper blade 121 formed in one edge with a thread-receiving slit 122 with longitudinal thread-engaging portion 123 in alinement with the thread-notch 120 of the blade 119. The blade 121 is secured by means of a screw 124 upon a seat formed therefor on the bracket 105. The waxing compartment is provided near the top with a forward extension 125 extending beneath and beyond the offset portion 56 of the take-up rock-shaft 55, and from the bottom of this extension rises a post 126 upon which is mounted by means of the screw-pin 127 the

grooved thread-guiding roller 128, one side of which is in substantial alinement with the inner end of the thread slit 123, while the other side of said roller is in substantial register with the thread aperture 57 of the rock-shaft 54.

The needle-thread is led from the source of supply through the guide-eye 109, between the tension disks 108, thence downwardly around the thread-wheel 115, upwardly through the thread-slit 123, over the guide-roller 128 and through the forward portion of the rock-shaft 54 to the tension-wheel 60, whence it passes to the needle as before explained. The several parts just described are so arranged and proportioned that when the movable stripper blade 119 is in retracted position, in which the inner portion of its notch 120 is out of register with the thread-slit 123, as represented in Fig. 14, the lead of the thread between the slit 123 and the thread-wheel 115 is nearly parallel with the rock-lever, while the lead of the thread between the thread-wheel 115 and the initial tension device 108 is oblique to the length of the rock-lever. Hence, when the thread is drawn through the waxing chamber or compartment to the stitch-forming mechanism, the tendency is for the thread passing around the thread-wheel 115 to throw the same rearwardly, thereby advancing the stripper-blade 119 into engagement with the thread leading through the slit 123, thus itself pressing upon one side of the thread and forcing the other side of the thread against the forward end of the slit 123, the feed of the thread causing the stripping of the same by this means of superfluous wax in which the roller 115 is normally submerged. It will be further observed that the greater the tension upon the thread the more intense will be the engagement of the stripper blades 119 and 121 upon the thread.

As in other machines employing hard wax for the needle-thread, portions of the frame are made hollow to form chambers for steam or other heating fluid. As herein shown, the head of the bracket-arm is formed in its upper portion with a steam chamber to which steam is admitted by means of the inlet pipe 129 from the source of supply. Circulation is established in this chamber through an exhaust fitting 130 tapped into the rearward side of the head 4, and through a circulation pipe 131 passing horizontally intermediate the arm 3 and the wax-pot and downwardly and then forwardly where it enters at 132 the steam chamber provided at the outer end of the work-supporting arm 2 adjacent to shuttle-race 43. It passes from the last mentioned steam chamber through the exhaust pipe 133.

The waxing chamber is formed in the lower portion at the forward side with an

external recess 134 to receive a heating block 135 which is formed with an upwardly and forwardly extending portion 136 having an aperture fitted to the pipe 131 by which it is supported. The end wall of the recess 134 is provided with a set-screw 137 which passes through the same and engages the side of the block 135 so as to press the same against the opposite end wall of the recess or cavity in order to establish a firm metallic contact between the two. As will be observed, the hanging of the block 135 upon the heated steam pipe 131 causes the conduction of heat from the one to the other, this heat being further conducted to the walls of the wax pot by contact of the block therewith as described. By this means, no special steam fittings are required for heating the wax, which latter is in practice kept of the required degree of consistency for permeating the needle-thread without injuring the same by overheating. As will be observed, the wax is introduced in the required quantity into the receiving compartment or reservoir of the wax-pot in lumps in the usual commercial form, and as it becomes heated by contact with the walls of the wax-pot it works through the apertures 104 in the dividing wall into the waxing chamber entered by the thread, which insures its being homogeneous where it touches the thread.

The present machine being of the "needle feed" type, means are provided for imparting to the needle frame 8 lateral movements crosswise of the cylinder bed 2. To this end, the driving shaft is provided adjacent the actuating crank 19 with a so-called "triangular" cam 138 formed with outer and inner concentric portions and intermediate eccentric or active portions. This cam is embraced by a yoke 139 formed at the lower end of a swinging lever 140 whose upper end is pivotally connected by means of the screw-stud 141 with the depending crank-arm 142 at the rearward end of a rock-shaft 143, mounted upon the front side of the bracket-arm 3 and carrying at its forward end a depending crank-frame comprising the collar 144, parallel arms 145 and connecting boss 146. The forward edge of the needle-frame is provided with a perforated lug 147 in which is secured by means of the nut 148 the shouldered pin 149 which enters an aperture in the boss 146 and serves to pivotally connect the crank-frame of the rock-shaft 143 with the needle frame. The needle-frame 8 is provided also with a rearwardly projecting lug 150 having a split socket in which is clamped by means of a screw 151 a bushing 152 with threaded perforation in which is fitted the threaded shank of a screw 153 passing through a slot 154 in the segmental member 155 of a depending arm 156 of the frame and having its head 153 countersunk in the rearward

face of a slide-block 157 fitted to a segmental seat 158 of taper cross-section in the member 155. As the fixed segmental seat 158 for the needle-frame slide-block 157 has substantially the same curvature as the arc of movement of the pin 149, it will be observed that in the lateral movements of the frame derived from the cam 138 its parallelism will be maintained. The stitch-regulating lever 159 is fixed at one end upon the rock-shaft 21, its other end projecting through a suitable aperture in the standard 1 at the front of the machine for convenient access by the operator, while its intermediate portion is divided or yoked at 160 to embrace the central portion of the vibrating lever 140, which latter is formed in opposite sides with segmental grooves 161 of V-shaped cross-section entered by correspondingly shaped fulcrum-blocks 162 formed with conical apertures which are entered by the center-screws 163 mounted in the yoke portion 160 of the lever 159. As will be observed, the position of the lever 159 determines the location of the fulcrum points 163 upon which the lever 140 vibrates, and hence determines the range of lateral movement in the line of seam of the needle-frame and the needle. The feed-cam 138 is so fixed upon the shaft 20 as to cause the lateral or feeding movements to be imparted to the needle while still in the goods after the needle-thread loop has been seized by the shuttle.

The presser-foot 164 is provided with the usual elongated needle-hole 165 and is provided with a shank 166 having at its upper end a transversely grooved member with a slot 167 entered by the fastening screw 168 and securing the same adjustably to a correspondingly shaped seat 169 formed upon a collar fixed to the lower end of the presser-bar 170 which is fitted to suitable bearings in the head of the bracket-arm and is provided at the top with a shouldered cap 171 to receive the lower end of a coiled compression spring 172 whose opposite end is similarly fitted to a shouldered plug 173 formed upon the lower end of the adjusting screw 174 secured against rotation by the lock-nut 175 in the threaded boss 176 of a thrust-rod 177 secured in a boss 178 upon the top of the bracket-arm member 4 by means of the set-screw 179. The presser-bar is flattened upon one side at 170° and has slidingly mounted thereon the sleeve 180 provided with laterally projecting spaced ears 181 between which is pivoted by means of the pin 182 the lever 183 having at its lower end a slot or fork 184 within which is pivoted by means of a pin 185 the cramping lever 186 having upon one side of its fulcrum point the jaw 187 adapted to enter a slot 188 in the lower end of the sleeve 180 and engage the flat portion 170° of the

presser-bar. The lever 183 is formed with an upward extension or lug 189 in which is adjustably secured and locked by means of the nut 190 the threaded outer end of a stop-screw pin 191 whose point enters a lateral cavity 192 in the sleeve 180. By adjusting the stop-pin 191, the initial position of the lever 183 is determined, and the point of operative engagement of the jaw 187 of the lever 186 with the presser-bar is fixed.

The apertured outer end of the cramping-lever 186 embraces a pin 193 by means of which it is pivotally connected with the forked lower end of a link 194 whose upper end is pivotally connected by means of a pin 195 with a lateral crank-arm 196 secured to the forward end of a rock-shaft 197 journaled within and longitudinally of the bracket-arm 3 and having fixed upon its rearward end the lateral crank-arm 198 connected by means of the screw-stud 199 with the eccentric-rod 200 having at its lower end the strap 201 embracing the actuating eccentric 202 upon the driving shaft 20. The eccentric 202 imparts to the rock-shaft 197, through the eccentric-rod 200 and crank-arm 198, rocking movements which are communicated to the cramping-lever 186 through the crank-arm 196 and link 194, which movements are ineffective for the greater part, but which become effective in lifting the presser-bar and the presser-foot when the cramping-lever 186 is raised sufficiently to seat its jaw 187 firmly upon the flat portion 170° of the presser-bar, which causes these parts to become locked together and to be lifted bodily in the continued upward movement of the link 194 with the crank-arm 196. The presser-bar is adapted to rise independently of the sleeve 180 in order to permit the presser-foot to accommodate itself to different thicknesses of material without affecting the action of the lifting mechanism thereon, and the sleeve 180 is normally pressed downward by a spring 203 surrounding the presser-bar and interposed between the top of the sleeve and the upper bearing of the presser-bar, whereby the forked lateral extension 184 at the lower end of the lever 183, which embraces the presser-bar 170, is caused to normally rest upon the top of the series of yielding washers 204 interposed between the same upon the presser-bar and the top of the lower presser-bar bearing, whereby noise and shock are prevented in the actuation of the presser-bar. The eccentric 202 is so set upon the shaft 20 as to cause the lifting of the presser-foot just as the needle is about to begin its lateral or feeding movement, so as to permit the work to be advanced by the needle without resistance.

Fixed to the lower portion of the presser-bar 170 above the presser-foot shank and

to the lower end of a vertical slide-bar 205 is the perforated boss 206 of a bracket having a rearwardly and upwardly extending arm 207 with a split bearing 208 in which 5 is adjustably secured by means of the clamp-screw 209 the hub 210 of a depending lever 211 carrying at its lower end a stud-screw 212 connected by means of a link 213 with a similar screw 214 tapped into a rearwardly 10 projecting ear of a lever 215 having at its lower end a slot 216 entered by a fastening screw 217 tapped into the upper end or shank of the stitch setting blade 218, whose lower end is shaped to embrace the individual stitches of a seam intermediate the needle punctures, in a manner well-known. The upper end of the lever 215 is pivotally connected by means of the stud-screw 219 with the lateral arm 220 of a rocker 221 carrying the center screws 222 which enter conical recesses in the opposite ends of the hub 210 of the lever 211, by means of which said rocker is mounted to oscillate upon the frame 206 207. The rocker 221 is provided 25 with an upwardly projecting arm 223 connected by means of a screw-stud 224 with one end of a link 225 whose opposite end is connected by means of the screw-pin 226 with a depending crank-arm 227 fixed upon 30 the forward end of the rock-shaft 197, which is preferably formed in practice integral with the crank-arm 196. The crank arms 196 and 227 are so proportioned and arranged that the rocker 221 is oscillated to 35 carry the stitch-setter through the slot 165 in the presser-foot 164 and into operative relation with the work just after the needle has accomplished a feeding movement and has emerged from the work; the stitch-setter 40 remaining in contact with the work until the needle is descending into the forward end of the needle aperture in the presser-foot to make a new puncture. In order that the stitch-setter may have a lateral movement in the line of seam to avoid interference with the needle, the link 213 is made shorter than the crank-arm 220, whereby the stitch-setter is drawn backwardly by the 45 link as the crank-arm 220 rises to withdraw 50 it from contact with the work, and is correspondingly advanced in its descending movement.

As will be observed, the support of the stitch-setter upon the bracket 206 207 rigidly connected with the presser-bar 170 causes it to partake of the rising and falling movements of the latter, and insures that both the presser-foot and the stitch-setter shall be disengaged from the work while 60 the needle is performing its feeding movement; it also insures that both shall be lifted clear of the work when the presser-bar is raised for the introduction or removal of the same. To provide for the manual lifting 65 of the presser-bar, the slide-bar 205 is pro-

vided upon its upper end with a fixed collar 228 carrying a lateral stud 229 upon which is mounted an anti-friction roller 230 adapted to be engaged upon the under side by a flat wearing face upon the forward end 231 of a lifting lever 232 mounted upon a fulcrum-stud 233 projecting from the bracket-arm 3 and having at its rearward end an eye 234 for attachment of a treadle rod in a manner well-known. 75

To adjust the point of application of the stitch-setter 218 relatively of the needle path, the lever 211 is provided with an ear 235 which is engaged upon the rearward side by an adjusting screw 236 carried by 80 a depending ear 237 of the frame member 207 and upon the front side by the point of an adjusting screw 238 passing through a lateral ear 239 of the boss 206. To adjust the fulcrum-point of the link 213 in the direction of seam, one or the other of the adjusting screws 236 and 238 is withdrawn to the required extent and the other advanced to press the depending ear 235 firmly against the same, the path of movement of 85 the stitch-setter carrying lever 215 being thus modified to suit the requirements of the work in bringing the stitch-setter into exact register with the stitches. 90

Having thus set forth the invention, what I claim herein is:— 95

1. In a sewing machine, the combination with the main-shaft provided with a crank, and stitch-forming mechanism including a reciprocating needle and a coöperating loop-taker deriving operative movements from said main-shaft, of a pitman-lever connected with said crank, a movable fulcrum for said pitman-lever with means for guiding it in a defined path, a rock-shaft, a take-up arm mounted upon said rock-shaft, a crank-arm also mounted upon said rock-shaft, an intermediate rocker provided with two crank-arms, a pitman connection between one of the crank-arms of said rocker and the crank-arm of said rock-shaft, and a pitman connection intermediate the second crank-arm of said rocker and the pitman-lever. 105 110

2. In a sewing machine, the combination with the bracket-arm, a needle-actuating shaft journaled in and disposed longitudinally thereof, and stitch-forming mechanism including a reciprocating needle operatively connected with said shaft and a coöperating loop-taker, of a rock-shaft arranged parallel with said needle-actuating shaft, a take-up arm mounted thereon at the forward end of the bracket-arm and provided with a thread-engaging member, thread-guides coöperating with the thread-engaging member of said take-up arm, and a continuously acting tension device mounted upon said take-up arm adjacent its supporting rock-shaft and deriving rocking movements therefrom. 115 120 125 130

3. In a sewing machine, the combination with stitch-forming mechanism including a reciprocating needle and a coöperating loop-taker and means for actuating them, of a 5 rock-shaft, a take-up arm mounted thereon and provided with a thread-engaging member, thread-guides coöperating with the thread-engaging member of said take-up arm, a variable tension device mounted upon 10 said take-up arm adjacent its supporting rock-shaft, and means mounted independently of said rock-shaft for controlling the action of said tension device.
4. In a sewing machine, the combination 15 with stitch-forming mechanism including a reciprocating needle and a coöperating loop-taker and means for actuating them, of a rock-shaft, a take-up arm mounted thereon and provided with a thread-engaging member, thread-guides coöperating with the thread-engaging member of said take-up arm, a variable tension device mounted upon 20 said take-up arm adjacent its supporting rock-shaft, and means mounted upon a stationary support into engagement with which 25 said tension device is brought in the operation of the take-up arm for varying the action of the tension.
5. In a sewing machine, the combination 30 with stitch-forming mechanism including a reciprocating needle and a coöperating loop-taker and means for actuating them, of a rock-shaft, a take-up arm mounted thereon and provided with a thread-engaging member, thread-guides coöperating with the thread-engaging member of said take-up arm, a tension device mounted upon 35 said take-up arm, and provided with uniformly 40 acting means whereby it is caused to impose a drag upon the thread, and means mounted upon a stationary support into engagement with which said tension device is brought in the operation of the take-up arm for increasing the normal action of the tension device.
6. In a sewing machine, the combination 45 with stitch-forming mechanism including a reciprocating needle and a coöperating loop-taker and means for actuating them, of a rock-shaft, a take-up arm mounted thereon and provided with a thread-engaging member, thread-guides coöperating with the thread-engaging member of said take-up arm, a tension device mounted upon 50 said take-up arm, a spring applied to said take-up device and acting uniformly to maintain a constant drag upon said tension device, and a yielding controlling member mounted upon a stationary support within the 55 path of movement of said tension device and acting periodically upon the tension device to augment the action of said spring thereon.
7. In a sewing machine, the combination 60 with stitch-forming mechanism including a reciprocating needle and a coöperating loop- 65 taker and means for actuating them, of a rock-shaft, a take-up arm mounted thereon and provided with a thread-engaging member, thread-guides coöperating with the thread-engaging member of said take-up arm, a variable tension device mounted upon 70 said take-up arm adjacent its supporting rock-shaft, and means mounted independently of said rock-shaft for controlling the action of said tension device, a yielding controlling member mounted upon a stationary support within the path of movement of said tension device and acting periodically upon the tension device to augment the action of said spring thereon, and means for adjusting the position of said controlling member.
8. In a sewing machine, the combination 75 with stitch-forming mechanism including a reciprocating needle and a coöperating loop-taker and means for actuating them, of a rock-shaft, a take-up arm mounted thereon and provided with a thread-engaging member, thread-guides coöperating with the thread-engaging member of said take-up arm, a tension device mounted upon 80 said take-up arm, a spring applied to said take-up device and acting uniformly to maintain a constant drag upon said tension device, to augment the action of said spring thereon, and means for adjusting the position of said controlling member.
9. In a sewing machine, the combination 85 with stitch-forming mechanism including a reciprocating needle and a coöperating loop-taker and means for actuating them, of a rock-shaft, a take-up arm mounted thereon and provided with a thread-engaging member, thread-guides coöperating with the thread-engaging member of said take-up arm, a tension device mounted upon 90 said take-up arm, a spring applied to said take-up device and acting uniformly to maintain a constant drag upon said tension device, a rocking pin mounted upon a fixed support, a spring lever having one end secured to 95 said rocking pin and the other end extended into the path of movement of said tension device to augment the action of said spring thereon, a lateral arm carried by said rocking pin, a stationary abutment adjacent the same, an adjusting screw for determining the normal position of said lateral arm relative to said abutment, and a spring for maintaining said parts yieldingly in said relation.
10. In a sewing machine, the combination 100 with stitch-forming mechanism including a reciprocating needle and a coöperating loop-taker and means for actuating them, of a rock-shaft provided with an axial thread aperture, a take-up arm mounted thereon and provided with a thread-engaging member, thread-guides coöperating with the thread-engaging member of said take-up arm, a variable tension device comprising a 105 thread-engaging member with one side in substantial alinement with the axial thread aperture of said rock-shaft, a supporting pin for said thread-engaging member journaled upon said take-up arm, a spring applied to said supporting pin and acting through it to impose a drag upon the thread-engaging member, and a yielding controlling member mounted upon a stationary support 110 within the path of movement of said pin and acting periodically through the same upon the tension device to augment the action of said spring thereon.
11. In a sewing machine, the combination 115 with stitch-forming mechanism including a reciprocating needle and a coöperating loop-taker and means for actuating them, of a rock-shaft, a take-up arm mounted thereon and provided with a thread-engaging member, thread-guides coöperating with the thread-engaging member of said take-up arm, a variable tension device comprising a 120 thread-engaging member with one side in substantial alinement with the axial thread aperture of said rock-shaft, a supporting pin for said thread-engaging member journaled upon said take-up arm, a spring applied to said supporting pin and acting through it to impose a drag upon the thread-engaging member, and a yielding controlling member mounted upon a stationary support 125 within the path of movement of said pin and acting periodically through the same upon the tension device to augment the action of said spring thereon.

- reciprocating needle and a coöperating loop-taker and means for actuating them, of a rock-shaft provided with an axial thread aperture, a take-up arm mounted thereon 5 and provided with a thread-engaging member, thread-guides coöperating with the thread-engaging member of said take-up arm, a variable tension device comprising a rotary peripherally grooved thread-wheel 10 having one side in substantial alinement with said axial thread-aperture, a headed supporting pin journaled upon said take-up arm and upon which the thread-wheel is mounted, a spring acting upon said supporting pin in pressing the head of the latter upon one side of the thread-wheel, and a yielding controlling member mounted upon a stationery support within the path of movement of said pin and acting periodically through the same upon the tension device to augment the action of said spring thereon.
11. In a sewing machine, the combination with stitch-forming mechanism including a reciprocating needle and a coöperating loop-taker and means for actuating them, of a rock-shaft, a take-up arm mounted thereon and provided with two longitudinally spaced thread-engaging members, a fixed thread-engaging member disposed intermediate the paths of movement of said spaced members, a relatively stationary thread-guide disposed beyond the paths of movement of the spaced thread-engaging members relative to said rock-shaft, and a thread-guiding member carried by the take-up arm adjacent the said rock-shaft from which the thread is led to said relatively stationary thread-guide.
12. In a sewing machine, the combination with stitch-forming mechanism including a reciprocating needle and a coöperating loop-taker and means for actuating them, of a rock-shaft, a take-up arm mounted thereon and provided with two longitudinally spaced thread-engaging members, a fixed thread-engaging member disposed intermediate the paths of movement of said spaced members, a relatively stationary thread-guide disposed beyond the paths of movement of the spaced thread-engaging members relative to said rock-shaft, and a tension device mounted upon the take-up arm adjacent said rock-shaft.
13. In a sewing machine, the combination with stitch-forming mechanism including a reciprocating needle and a coöperating loop-taker and means for actuating them, of a rock-shaft, a take-up arm mounted thereon and provided with two longitudinally spaced thread-engaging members, a fixed thread-engaging member disposed intermediate the paths of movement of said spaced members, a relatively stationary thread-guide disposed beyond the paths of movement of the spaced members.
14. In a sewing machine, the combination with stitch-forming mechanism including a reciprocating needle and a coöperating loop-taker and means for actuating them, of a rock-shaft, a take-up arm mounted thereon and provided with two longitudinally spaced thread-engaging members, a fixed thread-engaging member disposed intermediate the paths of movement of said spaced members, and provided with means of adjustment in substantially the direction of movement of said spaced members, a relatively stationary thread-guide disposed beyond the paths of movement of the spaced thread-engaging members relative to said rock-shaft, and a thread-guiding member carried by the take-up arm adjacent the said rock-shaft from which the thread is led to said relatively stationary thread-guide.
15. In a sewing machine, the combination with stitch-forming mechanism including a reciprocating needle and a coöperating loop-taker and means for actuating them, of a rock-shaft, a take-up arm mounted thereon and provided with two longitudinally spaced thread-engaging members, a fixed thread-engaging member disposed intermediate the paths of movement of said spaced members, a rigid arm affording a support for said intermediate thread-engaging member, a stud-screw by means of which said rigid arm is secured for lateral adjustment upon a stationary member of the machine, a relatively stationary thread-guide disposed beyond the paths of movement of the spaced thread-engaging members relative to said rock-shaft, and a thread-guiding member adjacent the said rock-shaft from which the thread is led to said relatively stationary thread-guide.
16. In a sewing machine, the combination with stitch-forming mechanism including a reciprocating needle and a coöperating loop-taker and means for actuating them, of a rock-shaft, a take-up arm mounted thereon and carrying a thread-engaging member, a stationary thread-engaging member intermediate the path of movement of the first-named thread-engaging member and said rock-shaft, a relatively stationary thread-guide disposed beyond the range of movement of the first-named thread-engaging member in relation to the stationary thread-

engaging member, guard-loops embracing said thread-engaging members, that embracing the first-named member extending in the direction of its operative movement and that 5 embracing the stationary member lying in the opposite direction, and a pair of spring-pressed thread-retaining plates extending intermediate said stationary thread-engaging member and the stitch-setting position 10 of the first-named thread-engaging member.

17. In a sewing machine, the combination with stitch-forming mechanism including a reciprocating needle and a coöperating loop-taker and means for actuating them, of a 15 rock-shaft formed intermediate its ends with a lateral cavity and with an axial thread aperture leading from said cavity to its forward extremity, a take-up arm fixed upon the forward end of said rock-shaft and 20 carrying a thread-engaging member, thread-guides coöperating with the thread-engaging member of said take-up arm, a tension device mounted upon the take-up arm and having a thread-engaging member with one 25 side in substantial alinement with the axial thread-aperture of said rock-shaft, a wax-pot extending beneath said rock-shaft, and a thread-guide disposed above said wax-pot and extending within the lateral cavity 30 of the rock-shaft and in alinement with its thread-aperture, and adapted to guide the thread from the wax-pot through said aperture to the tension device.

18. In a sewing-machine, the combination with stitch-forming mechanism including a 35 reciprocating needle, and a coöperating loop-taker and means for actuating them, of a rock-shaft formed intermediate its ends with a lateral cavity and with an axial thread-aperture leading from said cavity to its forward extremity, a take-up arm fixed upon the forward end of said rock-shaft and carrying a thread-engaging member, 40 thread-guides coöperating with the thread-engaging member of said take-up arm, a tension device mounted upon the take-up arm and having a thread-engaging member with one side in substantial alinement with the axial thread-aperture of said rock-shaft, a wax-pot extending beneath said rock-shaft, 45 a thread-guide disposed above said wax-pot and extending within the lateral cavity of the rock-shaft and in alinement with its thread-aperture, and adapted to guide the thread from the wax-pot through 50 said aperture to the tension device, and a thread-stripper adapted to act upon the thread in its passage from the wax-pot to the last named thread-guide.

In testimony whereof, I have signed my 55 name to this specification, in the presence of two subscribing witnesses.

OTIS E. BROWN.
